(57) **CLAIM**

The ornamental design for a head mounting frame of head mounted display, as shown and described.

DESCRIPTION

FIG. 1 is a perspective view of a head mounting frame of head mounted display showing my new design;

FIGS. 2-8 are different perspective views of the head mounting frame respectively;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof; and,

FIGS. 15-16 are different perspective views showing a head mounted display being worn on a user's head by the head mounting frame.

The broken line portions of the head mounting frame of head mounted display in FIGS. 15-16 represent unclaimed portions of the claimed design and form no part thereof.
